CLAIM

The ornamental design for a leg for a desk, as shown and described.

DESCRIPTION

FIG. 1 is a perspective view of a leg for a desk showing my new design;

FIG. 2 is a front elevational view thereof;

FIG. 3 is a rear elevational view thereof;

FIG. 4 is a left side elevational view thereof; with the right side being a mirror image of that shown;

FIG. 5 is a top side elevational view thereof; and

FIG. 6 is a bottom side elevational view thereof; and,

FIG. 7 is a perspective view thereof, the broken line showing of a desk is for illustrative purposes only and forms no part of the claimed design.
